RHEOSTAT AND THE LIKE

Newton C. Schellenger, Elkhart, Ind., assignor
to Chicago Telephone Supply Company, Elkhart, Ind., a corporation of Indiana

Application October 26, 1931. Serial No. 571,101

6 Claims. (CL 201—55)

This invention relates to a process of making rheostats and the like.

It is old in the prior art to provide rheostats consisting of a cup-like metallic frame which is lined by a suitable insulation, and contains a resistance strip disposed inside of the shell and against the insulation lining. The present invention relates to the manufacture of a rheostat of this kind, and refers more particularly to an improved process for securely fixing the resistor strip in place in the shell.

Insulating materials such as fiber, certain phenol condensation products, and the like, are somewhat hygroscopic, and will absorb a certain amount of moisture. The materials expand as moisture is absorbed and contract as it is expelled. My improved process makes use of this property of insulating material to rigidly bind the resistance strip and insulating lining in the metallic shell of a rheostat.

In the preferred embodiment of my invention, sheets of insulation of suitable thickness and character for the purpose desired are thoroughly dehydrated in any convenient manner and while dehydrated are blanked into strips of shape and size determined by the device being manufactured. After the blanking is completed these strips are stored under such conditions that there is no likelihood of their absorbing moisture. The insulating strip upon which the resistance unit is to be wound is taken from this storage device and the wire is wound upon it under conditions which insure that the absorption of moisture will be negligible. If necessary after the winding operation is completed the units are returned to a suitable storage device where they remain until needed under conditions which prevent the absorption of the moisture by them.

The lining insulators with which the metallic shell or frame of the device is lined are similarly blanked from dehydrated insulation and stored in such a manner that they will not absorb moisture.

Upon assembly of the unit, the insulating lining is first placed within the shell with its ends overlapping, and then expanded mechanically to bring its ends in alignment and abutting each other. The terminals and other auxiliary devices are placed in the shell against this insulation and the resistance strip then placed inside of such devices. The ends of the resistance strip are overlapped and it is expanded mechanically to bring those ends into alignment and to abut them against each other. This compresses the strip under considerable pressure against its own hoop

strength, and it is held by the tension in the metallic shell itself.

The process is completed by first allowing the insulation of the rheostat to absorb a certain amount of water, which causes the insulators to expand and more firmly bind themselves in the metallic shell. After the required amount of water has been absorbed the moisture content of the strip is maintained constant by a sealing means which prevents both the evaporation of moisture from the unit and the absorption of additional moisture by it.

The rheostat is finished by attaching the contactor and other devices. However, this part of the manufacture of a unit is not of the essence of the present invention.

Thus it will be seen that my invention makes use of the well known properties which certain insulating material has when its moisture content is allowed to change, in such a manner that these properties may be utilized to securely bind the elements in the frame of a rheostat or other similar device.

My invention will best be understood by reference to the accompanying drawings in which sufficient details of the construction of a rheostat are shown to permit a clear understanding of the invention, and in which:

Figure 1 is a diagram illustrating the manner of blanking the insulators from a sheet of dehydrated insulation;

Figure 1a is a similar view illustrating the blanking of the winding strip from a sheet of dehydrated material;

Figure 2 is a plan view of one of the insulators so prepared;

Figure 3 is a similar view of a companion insulator;

Figure 4 is a plan view of the resistor unit after it has been wound;

Figure 5 is a similar view of the resistor unit after it has been trimmed preparatory to insertion in the frame or shell of the rheostat;

Figure 6 is a perspective view of a shell with the insulator lining in place in it;

Figure 7 is a cross sectional view of a partially assembled rheostat with the expanding device in place in it;

Figure 8 is a view similar to Figure 7 with the expanding device in its operated position;

Figure 9 is a plan view of the rheostat at the end of the next step in the process of assembly;

Figure 10 is a cross sectional view taken substantially along the line 10—10 of Figure 9 show-

ing the rheostat with the expanding member in place in it;

Figure 11 is a view similar to Figure 10 after the expanding member has been operated and removed and diagrammatically illustrating a succeeding step in the process;

Figure 12 is a fragmentary cross sectional view similar to Figure 11 and diagrammatically illustrating another step in the process of my invention;

Figure 13 is a plan view of a completely assembled unit made in accordance with the teachings of my invention; and

Figure 14 is a plan view of a modified form of shell which may be used within the process of my invention.

Referring now to the drawings in more detail, a sheet of suitable insulation 1 is thoroughly dehydrated to bring its moisture content down to a very low figure. This insulation may be fiber, or a phenol condensation product composed of fiber insulating material bonded together with a phenol condensation binder commonly known as bakelite. In any event, the insulating material is fibrous in nature and will expand somewhat upon absorbing moisture and contract as the moisture is expelled from it. The dehydration of the insulating sheet 1 may be carried on in any preferred manner such as by heat or vacuum treatment, or a combination of these two treatments.

Certain insulating materials of this kind are known to expand more in one direction with respect to their grain than in the opposite direction when they are permitted to absorb moisture, and if the sheet of insulation 1 is of this nature it is carefully noted in which direction maximum expansion will occur, so that the insulating devices blanked out of it will be formed with their longitudinal axes lying in the direction of maximum expansion.

In Figure 1 I have illustrated by the arrows 2 the direction in which the maximum expansion will occur when the sheet 1 is permitted to absorb moisture. Insulators 3 and 4 are shown in dotted lines, these insulators being blanked out of the sheet 1 by a suitable punch press operation. The particular shape and size of the members 3 and 4 is obviously shown by way of example as this will be determined by the particular requirements of the device being manufactured.

In Figures 2 and 3 I have shown insulators 3 and 4 blanked from a sheet such as the sheet 1. These particular insulators will be recognized as the lining members employed in the formation of a tandem type rheostat such as is shown in my copending application Serial No. 518,281, filed February 25, 1931. The insulator 3 contains projecting bosses 6 registering with depressions 7 in the insulator 4 to position the two halves of the tandem rheostat in definite relation with respect to each other. Insulators 3 and 4 also contain circular openings 8 and slit-like openings 9 for purposes which will hereinafter appear.

After the members 3 and 4 have been blanked they are stored under such conditions that there is no likelihood of their absorbing moisture. Since the members 3 and 4 are highly dehydrated they are inclined to be somewhat brittle and must be carefully handled to prevent them from breaking and also to prevent them from absorbing of moisture before it is desired that they should. I have found that a temperature controlled oven is a convenient storage receptacle for these members after they have been blanked and before

they are needed for assembly in a unit. By maintaining the temperature of the oven high and its moisture content low, the amount of moisture that is absorbed by the members 3 and 4 while they are in it can be kept negligible.

In Figure 1a, I have illustrated the manner of blanking the strip 5 from a sheet of dehydrated insulation 1', the direction of maximum expansion being indicated by the arrow 2'. Preferably this sheet 1' is composed of a fibrous phenol condensation product which is somewhat thicker than the sheet 1 from which the insulators 3 and 4 are blanked. The size and shape of sheets 1 and 1' are shown by way of example only.

Certain materials such as fiber, become brittle when dehydrated and under such circumstances I contemplate partially dehydrating the sheet prior to blanking and then further dehydrating the forms blanked from it. I have found that materials of this kind can be successfully worked without excessive breakage when their moisture content is about 50% normal, and that the forms blanked from such a sheet can be assembled when their moisture content is still further reduced, say to about 10% normal. These figures will of course vary with the material used, and I am not to be limited by them. Certain other materials can be completely dehydrated without rendering them too brittle to handle.

The strips 5 similarly blanked from the dehydrated sheet 1' are wound with a wire resistance winding 10 which may be composed of two sections 11 and 12 joined together by a suitable coupling means 13. The exact details of this winding will of course vary to meet the requirements of the particular unit being fabricated. Care is taken during the winding operation so that the amount of moisture absorbed by the insulator 5 is kept down to a minimum. After the units have been blanked and before they are wound, and after they have been wound and before they are needed in assembly, they are preferably stored in a receptacle suitably adapted to prevent any great amount of change in their moisture content.

After these insulators have been blanked and wound in the foregoing manner, they are ready for assembly into the unit being manufactured. For example, if the unit is a rheostat it may conveniently comprise a cylindrical metallic shell 15 having closed end 16 and side walls 17 disposed as a flange projecting from the closed end 16. A suitable disc of insulating material 18 is first disposed within the shell at the junction of its closed end 16 and walls 17, and an insulator such as 3 is disposed around the inside surface of the flange section of the wall 17 and against the disc 18, as shown in Figures 6, 7 and 8. It will be noted that the length of the insulator 3 is greater than the perimeter of the inside surface of the wall 17 of the shell and that the ends of the insulator therefore overlap as at 19. The amount of this overlap may be varied and will of course depend upon the thickness of the stock from which the insulator 3 is blanked.

The next step in the process consists in expanding the insulator 3 to position it firmly against the inside surface of the wall 17 of the shell and with its ends abutting. This operation may be performed in a number of ways, for example, a cylinder 20 composed of resilient material such as live rubber may be placed in the shell 15 where it loosely fits within the insulator 3. The cylinder 20 is sufficiently long that it projects well above the free edge of the wall 15.

17 of the shell and the edge of the insulator 3 lying thereagainst.

The unit may then be conveniently placed in a suitable press and the plunger 21 thereof brought down against the projecting end of the resilient cylinder 20 to compress that cylinder longitudinally of its axis, the closed end 16 of the shell being suitably supported upon a table 22 of the press during this operation.

10 Compression of the cylinder 20 along its longitudinal axis will expand it radially and thus cause it to force the insulator 3 tightly against the wall 17 of the shell. If necessary, sufficient pressure may be exerted by the plunger 21 to cause the cylinder 20 to expand sufficiently to force the wall 17 of the shell outward slightly. This will obviously increase the perimeter of the inside surface of the wall 17 and the ends of the insulator 3 will be aligned in abutting relation as shown at 23 in Figure 8. When the pressure is removed from the block 20, that block will spring back into its normal shape, and the insulator 3 will be held in the shell by its own hoop strength in compression.

25 As will be seen in Figure 6, the shell 15 contains generally rectangular openings 24 in its wall 17, and the insulator 3 is positioned in the shell in such a manner that the slots 9 in it register with these rectangular slots in the shell. The next step in the operation of assembling the units consists in pushing terminals such as 27 through the slot 9 in the insulation and through the slot 24 in the shell preparatory to receive the resistor unit 10. This unit 30 is then removed from its storage place and trimmed so that its length corresponds accurately to the inside perimeter of the lined shell. As will be seen in Figure 4, the unit is blanked somewhat longer than is required and contains 35 oval shaped indentations 25 in its opposite end. After the unit has been trimmed accurately to length these indentations are semi-circular as shown at 26 in Figure 5, and are employed for a purpose which will hereinafter appear. The 40 unit is immediately placed inside of the shell against the insulator 3 and upon the disc 18 located therein, with its ends overlapping as shown at 28 in Figure 9. The overlapping ends are located midway between the slot 24 in the shell as shown.

A resilient block 29, similar to the block 20, is next inserted inside of the unit and compressed, as shown, to expand the unit 10 radially outward against the insulator 3. This 45 expansion may also be sufficient to expand the wall 17 of the shell, and is continued until the overlapped ends 28 of the unit 10 are aligned in abutting relation to each other as shown at 30 in Figure 11. It will be noted that the two semi-circular indentations 26 now register to form a generally circular opening in the strip 10, which is aligned with a circular opening 31 in the shell, for a purpose which will hereinafter appear.

50 After the block 29 has been sufficiently compressed to expand the resistance strip 10 into the desired position, pressure on it is removed and it is allowed to contract back into the shape shown in Figure 10, and it is then removed from the unit. The resistor strip 10 is now held in place in the shell by its own hoop strength in compression.

The next step in the process of manufacture of a unit consists in hydrating the insulators 3 and 10. In Figure 11 I have diagrammatically

illustrated a method of doing this, which consists of spraying the insulation by finely divided spray forced out of the nozzle 32 of a suitable pressure gun. This spray is preferably composed of chemically pure water, and the insulators 10 and 3 are quite thoroughly wetted by it. Obviously this is but one of the many ways by which moisture can be added to the unit, and is shown by way of example only. If desired, the units may be passed to a region of humid air, such as for example, a steam chamber, at such a rate that they will remain in it sufficiently long to permit the insulators 3 and 10 to absorb the desired quantity of moisture. This and many other obvious methods may be employed to introduce moisture into the insulators within the teachings of my invention.

80 After the insulators have absorbed a certain quantity of water, and have tended to expand longitudinally, the various parts of the assembly will be very tightly clamped together. Since the insulator 10 was placed under compression when the expansion member 29 was removed, any slight elongation of it along its longitudinal axis, or slight thickening of the material radially, will cause an appreciable increase in radial pressure between the shell of the unit and the insulator 10. The insulator 3 will likewise absorb moisture and expand so that the pressure by which the unit 10 is held in the shell is greatly increased.

85 Expansion of the unit 10, while it goes primarily along the longitudinal axis of the strip, since that strip was blanked out of the sheet in such a manner that the greatest expansion will occur along its longitudinal axis, it will nevertheless 90 expand in all directions. This obviously tightens the resistance winding and securely binds it in place on the insulator so that it will not be displaced thereon by the contactor of the rheostat as that contactor is moved over the resistance.

95 After the insulation has been allowed to absorb a certain amount of water it is necessary that the moisture content of it be maintained substantially constant if the binding pressure between the insulation and the metallic shell is to 100 be maintained constant. To this end I propose to coat the insulation with a film of sealing material, such as for example, oil. In Figure 12 I have 105 illustrated dropping drops 33 of oil onto the insulators 3 and 10 from a suitable receptacle 34. Obviously this is merely a diagrammatic illustration and the oil or other sealing material may be applied in any preferred manner. If desired, the entire unit may be immersed in oil; however, this is a less desirable method of applying it since 110 the entire shell must then be cleaned to remove the excess.

115 After the resistance unit and insulator have been coated with a sealing material, a suitable metallic washer 40 is placed inside of the resistor 120 10 and a rivet 41 is projected through it and through the opening formed by the two semi-circular openings 26 in the resistance unit 10 and through the circular opening 31 in the shell which is in registration therewith. A suitable 125 terminal 42 is placed over the projecting end of the rivet and that end is then riveted over as at 43 to securely lock the terminal in place upon the shell.

130 While this method of attaching the terminal 42 to the shell also binds the resistor unit 10 in place in it, it is not relied upon for support of the resistor in the shell. The rheostat is finished by adding a suitable contactor 44 which for example may be of the type shown in my above mentioned 135

copending application, although obviously any preferred type of contactor may be used within the teachings of my invention.

In certain instances it may be desirable to provide a shell which has a very appreciable amount of flexibility radially, and to this end I may use a shell such as is shown in Figure 14. This shell comprises a circular plate 45 having a flange 46 rising out of its outer edge, and this flange 46 is provided with a plurality of outwardly projecting corrugations 47 uniformly spaced around it. The flange may also be provided with a pair of larger corrugations 48 adapted to receive the terminals 27 of the rheostat; however, the use of such corrugations is not necessary and if desired they may be omitted.

Obviously when a shell of the type shown in Figure 14 is used and expanded by the application of pressure radially outward through expansion of a member such as 29, the corrugations 47 and 48 will tend to flatten out and thereby increase the length of the inside face of the shell. When the radial pressure is removed these corrugations will tend to assume their original shape, and the perimeter of the inner surface of the shell will be thereby reduced and the shell will therefore exert considerable pressure against the insulator strips disposed within it.

In the foregoing description of my improved process I mention the use of two expanding members 20 and 29 the first of which is used to expand the lining insulator of the shell into place and the latter to expand the resistance carrying strip into place. In the manufacture of tandem rheostats in which the lining insulators are comparatively thick, the use of two expanders of this type may be highly desirable. In the manufacture of single unit rheostats, there is no necessity of having the insulation lining of the shell so thick, and it may be convenient to use but a single expanding member which is applied after the lining and the resistance carrying strip are positioned in place in the shell. I am not therefore to be limited to the precise details described in the example given by way of illustration.

While I have chosen to show my invention by illustrating its adaptation to the manufacture of rheostats, I have done so by way of example as it is obviously capable of being applied wherever it is desired to retain a fibrous member within a cup-like shell under its own pressure. I am therefore to be limited only by the scope of the appended claims.

Having thus complied with the statutes and shown and described a preferred embodiment of my invention, what I consider new and desire to have protected by Letters Patent is pointed out in the appended claims.

What is claimed is:

1. A rheostat comprising a cup-like metallic shell, a plurality of corrugations projecting radially outward from said shell, an insulating member lining said shell, a resistance strip slightly longer than the inner perimeter of said insulating lining disposed within said shell and being compressed to cause abutment of its ends against its own arch strength by compression in said shell and corrugations to lock the strip and insulating member in place in the shell, and a contactor pivotally mounted on said shell and engaging said resistance strip.

2. A rheostat comprising a shell consisting of

a closed end metallic cylinder whose walls are slightly flexible, an insulation lining in said cylinder, a wire wound resistance strip having a length slightly greater than the perimeter of the surface of the lining against which it is adapted to bear so that when the strip is disposed in said shell with its ends abutting it is compressed against the tension of the shell and locks itself and the insulation in the shell, a sealing material on said strip for maintaining its moisture content substantially constant, and a contactor mounted on said shell and engaging said resistance.

3. A rheostat comprising a shell consisting of a closed end metallic cylinder whose walls are slightly flexible, an insulation lining in said cylinder, a wire wound resistance strip disposed in said shell with its ends abutting, terminals engaging the ends of said resistance and disposed between it and said insulation, the normal length of said strip being slightly more than the perimeter of the surface of the lining against which it is adapted to bear so that the strip, when compressed against the tension of the shell to cause abutment of its ends, locks itself, said terminals, and the insulation in the shell, a sealing material on said strip for maintaining its moisture content constant, and a contactor mounted on said shell and engaging said resistance.

4. A rheostat comprising a shell consisting of a closed end metallic cylinder whose walls are slightly flexible, a fibrous insulation lining in said cylinder, a wire wound resistance strip adapted to be disposed in said shell with its ends abutting, the normal length of said strip being slightly more than the perimeter of the surface of the lining against which it bears so that the strip, when compressed against the tension of the shell, locks itself and the insulation in the shell, a sealing material on said strip for maintaining its moisture content constant, and a contactor mounted on said shell and engaging said resistance.

5. A rheostat comprising a shell consisting of a closed end metallic cylinder whose walls are slightly flexible, an insulation lining in said cylinder, a wire resistance unit wound on a fibrous insulation strip disposed in said shell with its ends abutting, the normal length of said strip being slightly more than the perimeter of the surface of the lining against which it bears so that the strip, when compressed against the tension of the shell, locks itself and the insulation in the shell, a sealing material on said strip for maintaining its moisture content substantially constant, and a contactor mounted on said shell and engaging said resistance.

6. A rheostat comprising a shell consisting of a closed end metallic cylinder whose walls are slightly flexible, an insulation lining in said cylinder, a wire resistance unit wound on a fibrous insulation strip disposed in said shell with its ends abutting, the normal length of said strip being slightly more than the perimeter of the surface of the lining against which it bears so that the strip, when compressed against the tension of the shell, locks itself and the insulation in the shell, a film of oil covering said strip to maintain its moisture content substantially constant, and a contactor mounted on said shell and engaging said resistance.

NEWTON C. SCHELLENGER.
